WARP DYE BEAM

Hubert M. Craig, Stanley, N. C.

Application July 24, 1937, Serial No. 155,371

4 Claims. (Cl. 242—123)

This invention relates to a perforated beam for dyeing and the like, and more especially to means for supporting a perforated cylindrical drum around which the yarn is placed prior to the dyeing operation. It is a standard practice to construct dye beams by providing a perforated cylindrical drum between two beam heads. The yarn is wound around this cylindrical, perforated portion, after which it is subjected to the dyeing operation and to other liquid treatment. During this treatment the perforated portion is subjected to much pressure and therefore, it is necessary to properly reinforce this perforated cylinder on its interior so that the pressure will not cause the same to buckle or collapse.

It is therefore, an object of this invention to provide a dye beam comprising a pair of heads between which is placed a perforated cylindrical member, said cylindrical member being supported on the interior portion thereof both longitudinally and axially, by struts and rings respectively. Both the struts and rings in the present instance, have contact with the interior periphery of the perforated cylinder thereby utilizing the entire intermediate framework between the two heads as a supporting means for the cylinder as well as giving added rigidity to the beam. Also, by providing a framework construction of this type, the longitudinal struts serve as spacer members for the head portions and thereby carry the entire stress between the two heads so that the perforated cylindrical member will not be subjected to any compressive stress. This is very important since such stress, when carried by the cylindrical member, often results in buckling or warping of the drum, especially when it is subjected to the pressure during a dyeing operation.

This construction is very important where stainless metal is employed for constructing the dye beam. In dyeing certain colors or shades, it is necessary to use a highly chemical resistant metal in order to avoid off-shades. Certain stainless metals, when subjected to temperatures necessary for welding, lose their stainless qualities. By providing the present type of construction, it is possible to eliminate welding and high temperature soldering, but at the same time, have a beam of the desired strength.

Some of the objects of the invention having been stated, other objects will appear as the description proceeds when taken in connection with the accompanying drawing, in which:

Figure 1 is an elevation with portions thereof broken away, of a dye beam made in accordance with the invention;

Figure 2 is a top plan view of Figure 1 with portions thereof broken away;

Figure 3 is a sectional view taken along line 3—3 in Figure 1;

Figure 4 is a sectional view taken along line 5—4 in Figure 1;

Figure 5 is a sectional view taken along line 5—5 in Figure 2;

Figure 6 is an enlarged, detail view showing the intersection point of the rings which give axial support to the perforated plates and the longitudinal struts which give longitudinal support thereto.

Referring more specifically to the drawing, the numeral 10 indicates suitable beam heads, each of which have a hole 11 in the central portion thereof, which hole is partially closed by a plurality of radially disposed spokes 12. At the intersection of the spokes 12, a hole 13 is provided which is penetrated by a suitable shaft, not shown, when the beam is placed in an operative position. Each of the beam heads also has a hub portion 14 in which rope grooves 15 are cut for accommodating a suitable rope by which tension is placed upon the beam.

The head portions 10 are secured in spaced relation to each other by suitable longitudinal struts 17. The ends of these struts are secured to the head portions 10 by a standard gusset connection which comprises a pair of angles 18, one angle being placed on each side of the ends of bars 17. Penetrating the upright legs of these angles 18 and the bar are bolts 19. The other legs of the angle 18 are adapted to fit against the proximate faces of beam head 10 and are secured thereto by stud bolts 20. The bars 17 are radially disposed about the hole 13 and the outer edges of the bars are adapted to support the interior surface of a cylindrical drum 25 which has perforations 25a therein. The bars 17 have at spaced intervals along the outer edges thereof suitable notches 26, which notches accommodate rings 27, said rings having their peripheries normally contacting the interior periphery of the cylindrical, perforated cylinder 25.

It is thus seen that both of the struts 17 and the rings 27, at their intersection, support the interior of the plate member or drum 25. This plate member has its ends embedded in annular cavities which are cut in the face of the head members 10, (Fig. 5); however, it should be stated that this embedding of the ends of the perforated plate is made only for the purpose of eliminating a crack between the head portions 10 and the end of the plate. The beam is so de-

signed that the longitudinal struts carry the entire stress between the head members 10, therefore no compressing stress will be placed upon the perforated cylinder 25. The ends of the perforated cylinder 25 have an additional support which comprises arcuate projections 29 which are integral with the face of head members 10 and which are disposed between the gusset connections for the bar 17. The perforated cylinder 25 is adapted to support yarn which is placed therearound and when the same is desired to be dyed or subjected to other liquid treatment it is placed under pressure so that the dye stuff will flow through the yarn and through the perforations 25a in the cylinder.

15 It is thus seen that I have provided a dye beam having the perforated yarn supporting surface supported on the interior portion thereof both longitudinally and axially so that the lightest, strongest, and most economical design can be made without resorting to welding, brazing or soldering which is detrimental to the stainless properties of the material from which the beam is constructed.

20 25 In the drawing and specification there has been set forth a preferred embodiment of the invention, and although specific terms are employed, they are used in a generic and descriptive sense only, and not for purposes of limitation, the scope of the invention being set forth 30 in the appended claims.

I claim:

35 1. A warp dyeing beam comprising a pair of heads separated by a plurality of longitudinal struts, means for securing the struts to the heads comprising a pair of right angle brackets, one leg of one bracket being fitted against and secured to one side of a strut, one leg of the other bracket being fitted against and secured to the other side of the strut, and the other leg of each bracket being disposed against the inner face of the head, a plurality of ring members encircling said struts and being flush-top at their intersection points, and a perforated cylinder supported by the exterior of said struts and ring members between said heads, and each of the cylinders fitting against its associated head.

40 45 50 2. In a warp dyeing beam having a pair of heads and a perforated cylinder therebetween, means for interiorly supporting said cylinder comprising longitudinal struts normal to the

proximate faces of said heads and having their ends secured to the heads, and a plurality of circular members normal to said struts, the exterior edges of said struts and circular members normally engaging the interior of said cylinder 5 to support the same, the means for securing the ends of the struts to the heads comprising a pair of right angle brackets, one leg of one bracket being fitted against and secured to one side of a strut, one leg of the other bracket being fitted against and secured to the other side of the strut, and the other leg of each bracket disposed against and secured to the inner face of the head.

3. A warp dyeing beam comprising a pair of heads and a perforated cylinder therebetween, 15 a plurality of longitudinal struts having their ends secured to the proximate faces of said heads and also being concentrically spaced about the center thereof, a plurality of annular members supported by said struts, the exterior edges of 20 the annular members and struts being concentric for interiorly engaging and supporting said cylinder, the means for securing the ends of the struts to the heads comprising a pair of right angle brackets, one leg of one bracket being fit- 25 ted against and secured to one side of a strut, one leg of the other bracket being fitted against and secured to the other side of the strut, and the other leg of each bracket disposed against and secured to the inner face of the head. 30

4. In a warp dyeing beam comprising a pair of heads and a perforated cylinder therebetween, means for supporting said cylinder comprising a plurality of longitudinal struts having their ends abutting the proximate faces of said heads 35 and being concentrically spaced about the center thereof, each of said struts having a plurality of spaced notches cut in the exterior thereof, annular members supported in said notches, both said annular members and said struts being 40 flush-top at said notches to thereby support said cylinder longitudinally and axially thereof, means for securing the ends of the struts to the heads comprising a pair of right angle brackets, one leg of one bracket being fitted 45 against and secured to one side of a strut, one leg of the other bracket being fitted against and secured to the other side of the strut, and the other leg of each bracket disposed against and secured to the inner face of the head. 50
